UNITED STATES PATENT OFFICE.

WILLIAM E. DEISCH, OF PORTLAND, OREGON.

GAS-ENGINE.

1,376,800.

Specification of Letters Patent.

Patented May 3, 1921.

Application filed July 3, 1919. Serial No. 308,377.

To all whom it may concern:

Be it known that I, WILLIAM E. DEISCH, a citizen of the United States, residing at Portland, in the county of Multnomah and 5 State of Oregon, have invented new and useful Improvements in Gas-Engines, of which the following is a specification.

This invention relates to gas engines, particularly to those of the multi-cylinder two 10 cycle type, and has for its object the provision of an improved engine in which each cylinder is formed in sections of different diameters and in which each cylinder has working therein a differential piston having 15 one section operating in one section of the cylinder constituting the explosion chamber and another section operating in the other section of the cylinder and constituting a charge forming device for compressing a 20 charge and delivering it to the explosion section of the next adjacent cylinder, an automatically opened and closed passage being provided for establishing communication between adjacent cylinders, action in the adjacent cylinders being mutual or reciprocal. 25

An important object is the provision of an engine of this character in which is provided a novel port and passage arrangement for effecting the transfer of a charge from the 30 compressing and charge forming section of one cylinder to the explosion section of the next adjacent cylinder, the invention being adaptable for use in connection with any two cycle motor having any even number 35 of cylinders set side by side in parallel relation or arranged as in a V-type motor or also arranged in opposed relation, and the structure may also be employed on engines using any of the well known types of fuel.

40 An additional object is the provision of an engine of this character which will be comparatively simple in construction and operation, which will be efficient and durable in use, and a general improvement in the art.

With the above and other objects and advantages in view, the invention consists in the details of construction to be hereinafter more fully described and claimed, and illustrated in the accompanying drawing, in 50 which

Figure 1 is a longitudinal sectional view of an engine constructed in accordance with my invention, and 55 Fig. 2 is a longitudinal sectional view on the line 2-2 of Fig. 1.

Referring more particularly to the drawing, I have shown an engine comprising cylinders designated broadly by the numerals 10 and 11 arranged side by side in parallel 60 relation, the engine being of the two cycle type. The cylinder 10 comprises sections 12 and 13 of different diameters, the former being the smaller and constituting the explosion section or chamber and the latter 65 constituting a compressing or charge forming chamber. Disposed within the cylinder 10 is a differential piston comprising two sections 14 and 15 working respectively in the sections 12 and 13 of the cylinder and 70 provided with piston rings 17. The piston is provided with the usual connecting rod 18 which is of course connected with the usual crank shaft and the cylinders are also adapted to be connected with the usual crank case, 75 these latter mentioned parts not being shown as forming no part of the present invention and not being essential to a clear understanding thereof. The cylinder 10 is also provided with a packing ring 19 at the lower 80 end of the section 12 and this packing ring firmly engages the section 14 of the piston for making a fluid-tight joint. The cylinders are also provided at their upper ends with the usual spark plug openings 20. 85

The cylinder 11 is identical in construction with the cylinder 10 and comprises the sections 21 and 22 within which are movable the sections 23 and 24 of the piston provided with the usual connecting rod 18. 90

Formed in the cylinders 10 and 11 are intake ports 25 and 26, respectively, and exhaust ports 27 and 28, respectively, and these various ports are connected with the proper manifolds, as shown, in the ordinary manner. Formed in the walls of the sections 14 and 23 of the pistons are passages 29 and 30, respectively, which at certain times are adapted to register with the intake ports 25 and 26, respectively. Formed in 95 the walls of the piston sections 15 and 24, are passages 31 and 32, respectively, which are at certain times adapted to register with openings or ports 33 and 34 formed in the sections 12 and 21 of the cylinders, respectively. The ports 33 and 34 communicate with a passage 35 formed in a member 36 disposed between the cylinders 10 and 11. When either of the passages 31 or 32 is in registration or communication with the 100 opening 33 or 34 as the case may be, communication will be established between the 105

110

cylinder section 13 and cylinder section 21 or between the cylinder section 12 and cylinder section 24, the former mentioned position being shown in Fig. 1.

5 The operation of the engine is as follows:-

Referring to the drawing it will be seen that the piston in the cylinder 10 is at the top of its stroke and that the piston in cylinder 11 is at the bottom of its stroke. When the piston in cylinder 10 starts on its down stroke a partial vacuum will be caused in the cylinder section 13 until the piston approaches the bottom of its stroke, whereupon the port 29 in the piston section 14 will register with the intake port 25, whereupon fresh mixture will be drawn through the port 25 and will pass into and fill the cylinder section 13 above the piston section 15. At the bottom of the stroke the burnt gases within the cylinder section 12 will pass out through the exhaust port 27. As the piston starts on its upstroke, the ports 25 and 27 will be covered and the mixture within the cylinder section 13 will be compressed until the upper end of the passage 31 registers with the opening 33 in the cylinder wall whereupon this compressed mixture will pass through the passage 35 in the member 36 and through the opening 34 into the cylinder section 21 of the cylinder 11. The piston in the cylinder 10 upon reaching the top of its upstroke is ready to repeat its cycle of operations. When the piston in cylinder 10 reaches the top of its stroke the piston in cylinder 11 is at the bottom of its stroke and the charge which was previously compressed within the cylinder section 13 is then in the cylinder section 21. As the piston in cylinder 11 then moves upwardly the mixture within the section 21 will then be compressed. As the piston in cylinder 11 subsequently starts on its down stroke and the port 30 registers with the port 26 at the lower limit of the stroke, fresh mixture will be supplied to the cylinder section 22 in exactly the same manner as it was supplied to the cylinder section 13, and the operation of the piston in cylinder 11 is identically the same as that of the piston in cylinder 10. It will be noted that the pistons and ports as well as the other parts, are so arranged that the action in each cylinder will be reciprocal to that in the other cylinder. Another feature of the invention is that the top walls of the piston sections 14 and 23 are so formed that when

a partially compressed charge is forced from either cylinder into the other, the charge will, upon encountering the curved top wall 60 of the piston, be deflected upwardly in the proper direction.

From the foregoing description and a study of the drawings it will be apparent that I have thus provided a simply constructed engine of the two cycle type which is adapted to have its cylinders arranged in various ways and which is provided with novel means whereby each cylinder partially compresses a charge and forces it into the explosion chamber of the next adjacent cylinder, the arrangement being such that the cylinders are reciprocal.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:-

An engine of the character described comprising cylinders each formed in two sections of different diameters, a piston within each cylinder formed in sections conforming to said cylinder sections and slideable therein, each cylinder being provided in the smaller section thereof with an exhaust port and being further provided intermediate the ends of the smaller section with an inlet port, the smaller section of each cylinder having further formed therein a port opposite the exhaust port, a passage member connecting said cylinders and establishing communication between said last named ports, the upper portion of the smaller section of each piston having formed in one side thereof a longitudinally elongated depressed portion forming a passage adapted to register with the inlet port and to establish communication therebetween and the larger section of the cylinder, said inlet port being arranged approximately at right angles to the exhaust port and said last named port, and the lower portion of the smaller section of each piston having formed in one side thereof a depressed portion forming a passage adapted to establish communication between the larger section of the cylinder and the smaller section of the other cylinder through said last named ports and said passage member.

WILLIAM E. DEISCH.
